WATER SPIDER

Virgil B. Moore and Stephen P. Tsoneff, Los Angeles, Calif., assignors to American Marine Engineering Corporation, a corporation of California

Application December 26, 1940, Serial No. 371,683

3 Claims. (Cl. 114—66.5)

Our invention relates generally to water craft adapted to travel on the surface of the water, and more particularly to craft which are especially adapted for use in warfare.

In modern naval warfare, it is important to provide defense units which may be used when regular warships are not available, and which may also be used in restricted areas and under conditions where the larger vessels are at a disadvantage. As a result, various navies have adopted or considered the adoption of small high-speed motor boats popularly known as "mosquito boats." Our invention is concerned with a naval vessel which we term a "water spider," which may be used for similar purposes, but which possesses many advantages not had by any other craft now available.

It is the major object of our invention to provide a small, high-speed surface vessel of great stability and maneuverability.

It is also an object of our invention to provide such a vessel which may be used under conditions so severe that other craft are immobilized.

Another object of our invention is to provide a craft which has a maximum of destructive power and requires a minimum crew.

It is a further object of our invention to provide such a vessel which may be quickly and easily produced in large quantities and at a very small cost.

One of the distinct advantages of a boat of this type is that it provides a relatively small and very elusive target, and consequently is adapted for rapid thrusts at a larger and more powerful enemy.

These and other objects and advantages of our invention will become apparent from the following description of a preferred form thereof, and from the drawings illustrating that form, in which

Fig. 1 is a plan view of our improved craft;

Fig. 2 is a side elevational view of said craft, with the bow or forward end to the left;

Fig. 3 is a partially broken away section showing the interior of the fuselage along the line 3—3 of Fig. 1;

Fig. 4 is a front elevational view of the craft as it appears in calm water;

Fig. 5 is a view similar to Fig. 4, but showing the action of the legs when encountering a lateral wave or swell; in both Fig. 4 and Fig. 5 the portions of the craft to the rear of line a—a in Fig. 2 have been omitted for the sake of clarity;

Fig. 6 is a side elevational view taken at 6—6

in Fig. 2 showing the method of connecting a leg to its respective pontoon;

Fig. 7 is an end elevational view of the pontoon connection taken at 7—7 in Fig. 6,

Fig. 8 is a cross-sectional view of one form of shock absorber which may be used in our invention; and

Fig. 9 is a horizontal section of the leg-pontoon connection, taken at 9—9 in Fig. 6.

Referring now to the drawings, and particularly to Figs. 1-5, it will be seen that our "water spider" consists generally of a streamlined fuselage or body portion 10, supported fore and aft by independently mounted vertically movable legs 11, 12, 13 and 14. The lower ends of said legs are pivotally attached to pontoons 15, 16, 17 and 18, respectively, which may be of the general type used on hydroplanes, and support the entire weight of the craft when it is at rest. The body is carried well above the water by the elongated legs which are spread relatively far apart at their bases, so that the craft has the general appearance of a water spider. By this type of construction an exceptionally high degree of lateral stability is given to the craft, enabling it to be turned sharply at high speeds without danger of capsizing.

The "water spider" is propelled by an airplane-type propeller 20 mounted at the rear of the fuselage 10, and is provided with stub wings 21 and 21a which help shield the propeller from spray while at the same time providing a certain amount of lift. The wings also provide space for gasoline and oil tanks, thus permitting the fuselage 10 to be made smaller and more streamlined, which decreases its vulnerability as a target.

Considering now the details of these parts, the fuselage 10 is preferably similar to an airplane fuselage, and may be of a semi-monocoque or shell type construction of high-strength aluminum alloy. As is customary in this type of construction, transverse frames are provided which are connected together by longitudinal members, and over this framework is applied the skin or shell. The body 10 may be divided into various compartments by means of shear-resistant bulkheads 22, which provide additional torsional stiffness, and water-tight doors may be provided in these bulkheads to allow members of the crew to pass from one compartment to another.

In the forward compartment 23 is mounted a retractable searchlight 24, and immediately aft of this compartment, is the gunner's cockpit 25,

Here is located a light cannon 26, such as a 37 m. m. for example, swivelly mounted so that it may cover a wide range, and in addition there are provided the minimum controls necessary to operate the craft, in case of emergency. Behind the gunner's compartment 25 is the pilot's compartment 27, provided with a complete set of controls and instruments used to operate the craft; and to the rear of this compartment is the cargo space 28. The cargo space may be filled with depth bombs 29, or may be used to carry soldiers, equipment, etc. In back of the cargo space we provide a mechanic's compartment 31, provided with an anti-aircraft gun 32 and a minimum set of operating controls, while aft of the mechanic's compartment 31 is the engine compartment 33 containing the engine 34. The sides of all crew compartments are preferably covered with armor plate, and it is to be understood of course that the relative position and equipment of the various compartments is given by way of example only.

Over the top of each of the crew compartments we provide a transparent cover 35 of plastic or other suitable material which may be pushed aside when the occasion demands. These covers have the effect of decreasing the wind resistance of the craft and at the same time keeping wind and spray from the crew members.

Motive power for the "water spider" is provided by means of the airplane-type pusher propeller 20 located at the stern of the vessel, and having its center near the top of the craft to avoid as much spray as possible. With the propeller 20 in this position, it is of course necessary to provide some means for transmitting the power from the engine 34 whose crankshaft is normally offset from the propeller hub, and to accomplish this, we prefer to use two sets of bevelled gears and an intermediate vertical drive shaft (not shown). In this manner it is possible to utilize an engine whose most efficient speed is different from the speed of maximum efficiency for the propeller. In this connection, we prefer to use a variable pitch propeller, and it is advisable to use one which may be put into reverse pitch to aid in navigating harbors, inlets, and the like. The engine 34 may be of any convenient style, but is preferably liquid cooled to permit maximum streamlining of the vessel.

The fuel supply for the craft may be carried in tanks (not shown) built in the stub wings 21 and 21a and provided with a leak-proof lining to prevent the loss of fuel if the tank is punctured. As previously mentioned, the wings 21 and 21a act as shields to reduce the amount of spray striking the propeller 20, and also provide a certain amount of lift for the vessel when it is traveling. The lift is usually relatively small, but may of course be increased by increasing the size of the wings or their angle of attack.

The craft is steered by means of an air rudder 39, preferably associated with a vertical fin 37 as is customary in airplane construction. The rudder and fin provide the principal control means, but it is also advisable to provide additional steering means consisting of rudders on the stern of the rear floats 17 and 18, to be described later. Torpedoes 40 of any suitable type may be suspended beneath the body of the vessel as shown, and they should be mounted near the nose of the craft to balance it properly and to decrease the effect of the turbulence caused by them on the rudder 36. This forward mounting of the tor-

pedoes 40 also permits a trap door 41 to be opened to allow the depth bombs 29 to be dropped.

To secure the maximum stability and maneuverability for which our craft is designed it is essential that the pontoons be vertically movable with respect to the body, and in our preferred form of craft as illustrated herein we mount the pontoons independently of one another in such manner that their vertical movement is all in a plane which is at a substantial angle to the longitudinal axis of the fuselage. By independently mounting the pontoons we make it possible for each pontoon to individually accommodate itself to the contour of the water at its point of contact therewith, without essentially affecting the position of the body. To further stabilize the craft and facilitate the vertical movement of the pontoons we attach them to the body in such manner as to cause them to move vertically with substantially no lateral rotation about their individual points of attachment to the legs, and with a minimum of horizontal movement with respect to the body.

Since all of the pontoons are preferably attached to the body in the same manner, we will only describe one leg structure in detail (the right front leg looking at the craft head-on), it being understood that this description likewise applies to the other legs.

In this form of our invention the means for attaching the pontoons to the body consists essentially of a jointed leg comprising a laterally extending normally horizontal member 42, and a vertically positioned upright member 43, said members being hinged at their point of connection. The lateral member 42 is hinged at its inner end to the body 16, and the upright member 43 is hinged at its lower end to the pontoon 16. It will be understood of course that these members may be made relatively massive if desired, employing for example I-beams with their narrow edge facing forward. However, we prefer to form them as trusses, employing high quality seamless tubing as illustrated in the drawings.

In the structure illustrated, the lateral member 42 instead of being a single massive member, is formed of two upper tubes 42 and 42a, and two lower tubes 42b and 42c, all of the same length and rectangularly positioned with respect to each other. Likewise the upright member instead of being formed of one piece, is fabricated of two vertical tubes 43 and 43a connected together by horizontal tubes 43b and 43c and cross braces 44. The lower portions of the upright member tubes 43 and 43a are bent forwardly and outwardly as indicated by the numerals 43d and 43e, these parts converging toward each other and joining at their lower ends adjacent their point of connection to the pontoon 16. It will be understood of course that all four of the laterally extending tubes 42, 42a, 42b and 42c are hinged at their inner ends to the fuselage, and at their outer ends to the upright truss formed of tubes 43, 43a, 43b and 43c to give a "knee action" effect.

From an inspection of Figs. 2 and 5 it will be seen that the hinge points of the upper and lower lateral members 42 and 42b are vertically aligned so that a parallelogram is formed whose horizontal sides are the members themselves, and whose vertical sides are the body 16 and the upright member 43. By this construction the upright 43 is maintained in vertical position no matter how the parallelogram is deformed (see

Fig. 5) and the pontoon 16 need not rotate about its own longitudinal axis to always present its full bottom surface to the water.

Since the legs 11, 12, 13 and 14 are pivotally connected to the body 10 and of course are not restrained by the water from moving laterally thereon, it becomes necessary to provide additional supporting means to maintain the body and the legs in their normal position with respect to each other, i. e. in the position shown in Fig. 4 of the drawings. This additional supporting or stabilizing means should also be resilient in order to allow the legs and their associated pontoons to assume different vertical positions above and below the normal in adapting themselves to uneven water conditions such for example as illustrated in Fig. 5, where the right leg and pontoon are riding the crest of a wave, and the left leg and its pontoon are in a trough.

Our preferred means for accomplishing this resilient supporting of the body consists of a shock absorbing tension strut 45 whose inner end is hingedly connected to the body 10 adjacent its base and preferably at the hinge connection of lower lateral member 42b, and whose outer end is hingedly connected to the upright 43 preferably at its point of connection to upper lateral member 42. While a single tension member 45 may be used, we prefer to employ a similar member 45a running from the body hinge of lateral member 42c to the top of upright member 43a. By reference to Fig. 5 it will be seen that when a pontoon and its associated leg are moved upwardly, the tension struts 45 are extended to form the longer diagonal of the deformed parallelogram, and when the float and its associated leg drop below their normal position, the tension strut is compressed since it is then the shorter diagonal of the deformed parallelogram. In the first case it is necessary that the strut 45 tend to return the members to their normal position by pulling downwardly on the leg, but in the second case (i. e. where the pontoon has dropped into a trough) the weight of the body will tend to normalize the structure as soon as the water becomes level again.

To provide the rapid and positive action which is necessary to stabilize the craft at high speeds, we prefer to make the shock absorbers 45 of the spring type such as illustrated in Fig. 8, it being understood that other forms, such as hydraulic and compressed air types may be used if desired. In the form shown, the shock absorber 45 has a lower arm portion 50 with a cylindrical housing 51 at its upper end, the housing being open at its upper end and having an internal shoulder 52 adjacent its opening. An upper arm portion 53 extends into the housing 51 and is provided with an external shoulder 54 at its lower end. A compression spring 55 surrounds the arm 53 between the shoulders 52 and 55 and urges them apart, thus making the member 45 as a whole a tension member. To provide cushioning for the arm 53 when it reaches its limit of inward travel we provide cushioning spring 56 which is interposed between the closed lower end of the housing 51 and the inner end of the arm 53. The spring 56 is normally smaller than spring 55 and while highly desirable is not essential. We prefer to use a compression type spring for the main spring 55, since if it breaks the broken ends will bear against adjacent turns of the spring, thus shortening its length but otherwise permitting it to act as before.

As previously mentioned, at the lower ends of

the legs 11, 12, 13 and 14, we provide pontoons 15, 16, 17 and 18 respectively. These pontoons are preferably of heavier construction than the customary hydroplane pontoon, since they are subjected to much severer service and since they are in continuous use instead of intermittent use. The principles underlying their construction are the same, however, and they should be designed to support twice the amount of weight they will normally carry. The floats 15, 16, 17 and 18 are pivotally attached to the legs 11, 12, 13 and 14, respectively, so that they may turn a limited amount about a horizontal transverse axis but not otherwise, thus making it possible for each individual float to adjust itself to the contour of the water surface and eliminating the danger of a float's "nosing down" into a wave. To provide a restoring moment which will return the float to its original position, we prefer to use the connection shown in Figs. 6, 7 and 9, the protective "boot" being removed to show more clearly the various members.

Each of the legs terminates at its lower end in a rocker 60 which has a pair of downwardly concave outer shoulders 60a and 60b and a depending central portion 60c shaped as a minor sector of a circle with its radial edges facing downwardly. The rocker 60 is mounted for rotation on a transverse axle 62 extending between a pair of upstanding side plates 61 and 61a which are parallel to the longitudinal axis of the pontoon and are rigidly fastened thereto through the medium of a base plate 63. The above mentioned parts are assembled so that the curved shoulders 60a and 60b bear and rotate on the side plates 61 and 61a respectively, and the center of the sector 60c is adjacent the base plate 63. The sector is preferably proportioned so that it can rock about 15° either side of vertical before one of its lower radial faces engages the base plate 63 whereupon further rotation is prevented.

To provide the required moment to restore the rocker 60 to its normal position we utilize a resilient member 64 which may be constructed like the tension struts 45, but is preferably formed with a simple compression rod 64a pivotally mounted to the base plate 63 and slidably within a cooperating cylinder 64b against a compression spring 64c. The cylinder 64b is pivotally mounted to one end of the rocker head 60 as seen best in Fig. 6. A similar restoring member 65 is connected to the other end of the rocker 60 and base plate 63 to provide the restoring moment against rotation of the rocker in the reverse direction.

To aid in steering the craft, especially at slow speeds, we provide rudders 46 on the rear pontoons 17 and 18, these rudders being controlled by the same means which controls the main rudder 36. The pontoon rudders are of particular use when the flow of air past the main rudder 36 is insufficient to permit it to control the craft.

The connections of the legs 11, 12, 13 and 14 to the pontoons 15, 16, 17 and 18, respectively, are covered with flexible water-tight boots, as are all other exterior pivoted connections, and suitable means are used to prevent electrolytic action at joints between dissimilar metals.

The unusual construction of the "water spider," and particularly its "knee action" legs, permits it to be used under conditions which would prohibit the use of conventional craft. The use of the independently mounted legs which are provided with shock absorbers provides a much smoother riding vessel, and this permits more

accurate aiming of the guns and torpedoes, and allows the crew members to perform their duties more efficiently, since strain and fatigue are greatly reduced. While there will undoubtedly be some weather conditions in which our "water spider" cannot operate, these same conditions will likewise immobilize conventional vessels, while on the other hand the "water spider" will be able to operate under many conditions which are too severe for conventional boats.

As an example of the performance to be expected from our invention, the following are the calculated characteristics of a "water spider" having a gross weight of 11,000 pounds, the results being calculated for both an eight hundred horsepower engine and a one thousand horsepower engine:

Performance summary

Eight hundred horsepower:

High speed	76.1 M. P. H.—
	66.1 knots
Cruising speed (75% power)	64.2 M. P. H.—
	55.8 knots
Endurance—high speed	6 hours
Range—high speed	466 miles
Endurance—cruising speed	8.9 hours
Range—cruising speed	589 miles

One thousand horsepower:

High speed	84.8 M. P. H.—
	73.7 knots
Cruising speed (75% power)	73.3 M. P. H.—
	63.7 knots
Endurance—high speed	4.8 hours
Range—high speed	415 miles
Endurance—cruising speed	7.12 hours
Range—cruising speed	533 miles

These performance characteristics, combined with the great stability of the "water spider," its economy of manufacture and operation, and its versatility, render it a valuable addition to the armed forces of any country, and also make it useful in Coast Guard work during peacetime. While we have shown and described a preferred form of our invention, it will be apparent that modifications may be made in the form and arrangement of parts without departing from the spirit of the invention, as defined in the following claims.

We claim:

1. A water craft which includes: a body; a plurality of pontoons capable of supporting said

body; jointed legs attaching said pontoons to said body to support the body above the water, each of said legs comprising a laterally extending normally horizontal member hinged at its inner end

5 to said body for movement above and below its normal position, a vertically positioned member hinged to the outer end of said lateral member and extending downwardly therefrom, its lower end being hinged to one of said pontoons, thereby allowing vertical movement of said pontoon with substantially no horizontal movement thereof with respect to said body; and resilient means connecting said legs to said body to support the body in normal position.

15 2. A water craft which includes: a body; a plurality of pontoons capable of supporting said body; jointed legs attaching said pontoons to said body to support the body above the water, each of said legs comprising upper and lower laterally

20 extending normally horizontal members hinged at their inner ends to said body for movement above and below their normal positions and hinged at their outer ends to the upper portion of a vertically extending member thereby forming a parallelogram with said body, the lower end of said vertical member extending downwardly and outwardly from its hinged connection with said lower lateral member to connect with one of said pontoons thereby allowing vertical move-

25 ment of said pontoon with substantially no horizontal movement thereof with respect to said body; and resilient means connecting said leg to said body to support the body in normal position.

30 3. A water craft which includes: a body; a plurality of pontoons capable of supporting said body; jointed legs attaching said pontoons to said body to support the body above the water, each of said legs comprising a laterally extending nor-

35 mally horizontal member hinged at its inner end to said body for movement above and below its

40 normal position, and a vertically extending member hinged to the outer end of said lateral member and extending downwardly therefrom to one of said pontoons, whereby upon rotation of said leg about said body said pontoon will move vertically with substantially no horizontal movement; and means associated with said legs and body tending to hold them in normal relation-

45 ship.
